Attorneys

UNITED STATES PATENT OFFICE.

ALBERT ZANDER, OF CHICAGO, ILLINOIS.

BURNER.

Application filed December 13, 1923. Serial No. 680,458.

To all whom it may concern:

Be it known that I, ALBERT ZANDER, a citizen of the United States, residing at Chicago, in the county of Cook and State 5 of Illinois, have invented a new and useful Improvement in Burners, of which the following is a specification.

My invention relates generally to burners employing fuel, in fluid condition, as, for 10 example, and by preference, any suitable gas; and my object generally stated is to so improve upon burners as hitherto provided that they will be better adapted to perform the work for which they are intended, and 15 in this connection effect substantially complete combustion of the fuel and render controllable, to the desired degree, the temperature of the products of combustion issuing from the burner.

20 A further object is to provide a burner which shall be eminently satisfactory for drying the molds in which steel castings, especially of large size, are formed and which in its use, shall present marked improvement over the present practice of 25 drying such molds which involve prolonged and expensive operations of drying in a furnace or by maintaining a fire beneath them in the open, both of these operations involving as a necessary incident, the high heating of the flask as well as the mold material containing the impression and not being productive of the desired uniformity of result or insuring certainty of unimpairment 30 of the molds.

35 Referring to the accompanying drawing:

Figure 1 is a view in sectional elevation of a burner especially adapted for heating molds, constructed in accordance with my 40 invention. Figure 2 is a view in side elevation of the structure shown in Fig. 1, the structure being viewed from the right hand side of Fig. 1. Figure 3 is a reduced sectional view taken at the line 3—3 on Fig. 1 and viewed in the direction of the arrows. Figure 4 is a similar view taken at the line 4—4 on Fig. 1 and viewed in the direction of the arrows; and Figure 5, a perspective view of a mold showing my improved 45 burner applied thereto in operative position for heating the mold.

50 The preferred, illustrated, construction of burner, as shown as of a form suitable for employing any desirable gas as the fuel, comprises inner and outer concentric shells

10 and 11 spaced apart to provide the annular space 12 closed at its bottom by a cup-shaped member 13, forming the lower end of the burner in the construction shown, the member 13 being provided on its upper surface with an upwardly-extending annular flange 14 extending into the space between the shells 10 and 11, these shells bearing against the upper surface of this member. The top of the burner is formed of the member 15 provided about its periphery with an annular laterally-extending flange 16 extending across the top of the annular space 12, this flange being provided with a depending annular flange 17 which extends 60 into the annular space 12 as shown. The parts thus described are held together, as through the medium of the threaded rods 18 shown as screwing at their lower ends into the flange 14 and extending upwardly 65 through the flange 16 with their upper, exposed, ends provided with nuts 19.

70 The member 15 contains at its central portion an air-inlet port 20 which opens into the upper end of the chamber 21 of the burner, the inlet port 20 being surrounded by an annular chamber 22 which opens into the chamber 21 through a circular series of ports 23, the chamber 22 containing an opening 24 for receiving fuel, as, 75 for example, gas supplied to it through a valved pipe 25 from any suitable source of gas supply.

80 The air inlet port 20 communicates with a pipe 26, valved at 27 and communicating 80 with a pipe 28 which leads from any suitable source of air under pressure.

85 The shell 10, shown as provided with a refractory lining 29, contains at intervals, a series of openings 30 which also extend 90 through the refractory lining 29, affording communication between the chamber 21 and the annular chamber 12. The openings 30 are shown as consisting of a plurality of 95 symmetrically disposed circumferential series of openings located in different vertical planes, though it will be understood that the arrangement of the openings 30 may be varied as desired.

100 The openings 30 are provided for the purpose of conducting into the chamber 21 at different points in its wall, streams of cooling, and preferably combustion-supporting, fluid, as, for example, air, for a purpose 105 hereinafter described, there being provided 110

to this end a pipe 31 valved at 32, which opens at one end through an opening 33 in the shell 11 into the annular chamber 12, and at its other end communicates with the 5 pipe 28.

The lower member 13 of the burner, which is also lined with refractory material, as represented at 34, contains an outlet 35 for the products of combustion, which communicates with a nozzle 36 shown as formed separately from the member 13, in accordance with the preferred construction and removably secured thereto to extend at its 10 passage 37 therethrough, in communication with the outlet 35, the nozzle 36 being shown as releasably secured to the member 13 between the flanges 38 thereof, by means of threaded studs 39 provided on the nozzle and extending through apertured lugs 40 on the 15 member 13, nuts 41 screwing on the studs 39 for securing the nozzle in place. The outlet of the nozzle may be of any desired form, but where the burner is to be used for heating a mold as hereinafter described, 20 it is preferred that said outlet be relatively long and narrow, and to this end the nozzle 36 is correspondingly shaped as represented in Figs. 2 and 5.

The member 13, in addition to the outlet 30 35, contains a lighting hole 42 shown as located at a point in the member 13 diametrically opposed to the outlet 35, the hole 42 being provided with a removable and replaceable closure 43.

To render the burner adapted for ready assembly with the mold to be heated, the burner is shown as provided with hooks 44 40 extending therefrom in the same general direction as the nozzle 36, and with hook carrying devices 45 carried by the burner at opposite sides thereof, as shown, and extending in the same general direction as the hook 44.

In the operation of the burner the 45 gas used as the fuel, is introduced into the chamber 22 through the pipe 25, from which it issues into the chamber 21 through the openings 23, air being simultaneously introduced into the chamber 21 50 through the pipe 20. In accordance with the preferred way of operating the burner, the amount of air supplied to the chamber 21 through the port 20 is sufficient to effect, when the mixture of the air and gas in the 55 chamber 21 is ignited, initial combustion only of the fuel. Simultaneous with the supplying of gas and air to the chamber 21 as stated, supplemental air is supplied from the pipe 31 to the annular chamber 12 from which 60 it discharges, in relatively fine streams, over a large area of the wall of the chamber 21, into the latter wherein it becomes mixed with the burning fuel. In accordance with the preferred way of operating the burner, 65 the amount of air introduced into the chamber 21 from the pipe 31 is sufficient, in supplementing the air introduced into this chamber through the pipe 20, to effect complete combustion of the fuel and in addition, under the control of the operator manipulating the valve 32, supply air to the 70 contents of the chamber 21 to such an amount as to effect a cooling of the products of combustion to the end that they shall issue from the nozzle 36 at the desired temperature 75 which may be varied, as desired, by regulating the amount of air passing through the pipe 31.

It may be here stated that it has been found in practice that not only may the 80 temperature of the products of combustion issuing from the nozzle 36 be accurately controlled, which is of particular importance in the heating of a mold to dry it, but complete combustion of the fuel in combination with the temperature control, may be effected without the occurrence of explosions or "howling" in the burner, these objectionable noises, and the vibrations of the 85 structure creating these noises, being eliminated by virtue of the admission of the gas and air separately into the inlet end of the combustion chamber, whereby a time factor during the initial stage of combustion resulting in the production of a slow or retarded combustion, is presented, and also to the feature of admitting the secondary air in the form of fine jets at different points along the combustion chamber resulting in the gradual admixture, with the burning 90 mixture, of air to support final combustion and preferably, as above stated, in an amount sufficient to effect the cooling of the products of combustion.

The application of the burner to a mold, 100 for drying the same, is illustrated in Fig. 5 wherein the cope and drag are represented at 46 and 47, respectively, the cope being supported in spaced relation to the drag as, for example, by means of the bars represented at 48 and interposed therebetween. The burner, being provided in any desired 105 number, depending upon the size of the mold to be dried, is then applied to the position shown in Fig. 5, in which position its hooks 44 and 45 hook over the frame of the cope 46 and its nozzle 36 extends into the space between the cope and drag, it being apparent that the flame issuing from the burner becomes spread throughout the 110 space between the cope and drag and results in the rapid drying of the mold material at the desired temperature at which the burner is set to operate.

While I have illustrated and described a particular construction embodying my invention, I do not wish to be understood as intending to limit it thereto as the same may be variously modified and altered without departing from the spirit of my invention.

tion. Furthermore, while I have shown and described my burner as applied to the heating of a mold, it will be readily understood that the burner is applicable to various other situations, the wide range of temperature control of which my device is capable adapting the burner to a wide range of usefulness.

What I claim as new, and desire to secure by Letters Patent, is:

1. A gas burner for drying molds or the like, comprising a hollow body affording a combustion chamber into which the fuel is introduced, means for supplying a combustion-supporting material for supporting initial combustion of said fuel, a discharge outlet for the products of combustion, and controlled means for supplying a final combustion-supporting and temperature-reducing medium under pressure at varying points between the point of initial combustion and the discharge outlet.

2. A gas burner for drying molds or the like comprising a hollow body affording a combustion chamber into which the fuel is introduced, the wall of said combustion chamber containing a plurality of inlets extending beyond the point at which initial combustion occurs, and means for conduct-

ing a fluid medium under pressure into said openings for discharge into said chamber.

3. A gas burner for drying molds or the like comprising a hollow body affording a combustion chamber, the wall of said chamber containing a plurality of inlets for the introduction of fuel into said chamber, and an inlet for a combustion supporting material, the wall of said combustion chamber also containing a plurality of inlets extending beyond said fuel inlets, and means for conducting a fluid medium under pressure into said openings for discharge into said chamber, beyond the point of initial combustion.

4. A gas burner for drying molds or the like comprising an inner and an outer shell spaced apart to afford an annular chamber, said inner shell affording a combustion chamber into which the fuel is introduced, said inner shell being provided with a plurality of inlets effecting communication between said annular chamber and said combustion chamber, and means for conducting a gaseous medium under pressure into said annular chamber for discharge through said inlets into said combustion chamber, beyond the point of initial combustion.

ALBERT ZANDER.
